ATTORNEY.

UNITED STATES PATENT OFFICE

2,268,040

COMBINATION ACCELERATOR AND BRAKE
PEDAL CONTROL

August D. Kumpf, Philadelphia, Pa.

Application September 27, 1941, Serial No. 412,540

5 Claims. (Cl. 192—3)

This invention relates to automobiles and has to do particularly with accelerator or gas feed controls which, through appropriate linkage, are ordinarily employed to open the butterfly valve of the conventional carburetor.

An object of the present invention is the improvement and simplification of controls of the nature described in my prior Patent No. 2,078,390, issued April 27, 1937. In that patent is shown and described a mechanism suitable for attachment to the ordinary brake pedal and floorboard by which a cooperation between the brake pedal and accelerator was accomplished in the interests of safety.

As I pointed out in that patent, many automobile accidents are caused by the confused motions of drivers who become excited in times of stress. In cases in which an unexpected obstacle or other hazard requires a quick application of brakes many drivers instinctively press the foot forwardly in the manner in which this is done to apply the brake. However, due to confusion and temporary loss of clear faculties it is unfortunate that some drivers neglect to move the foot from the accelerator button or gas feed control pedal before the forward pressure is applied. Thus, an accident is hastened rather than avoided because the increased speed of the car may make stopping impossible if the driver finally realizes his mistake.

In my prior patent I attempted to provide mechanism of a character which would reduce the danger brought about by the involuntary forwarding motion of the foot and would capitalize on this involuntary motion so as to bring the car to a more rapid halt. The mechanism I employed to accomplish my purpose was more complicated and expensive than I conceive to be necessary in the light of my present invention.

A more detailed object of this invention is the accomplishment of all of the beneficial objects of my prior patent without the disadvantages of high cost, complicated and special parts and without changing ordinary driving habits or positions to any great extent.

More specifically, I accomplish these objects by establishing a pivotal connection between the accelerator rod and a depressor bar which carries a head of a nature similar to the ordinary accelerator button. The pivoting action between the depressor bar and accelerator rod is resisted by a spring and lug arrangement at all times except when the driver's foot is moved forwardly into brake applying position and at that time pressure on the spring urged accelerator rod is

released to close the conventional butterfly valve. Various other and more detailed objects and advantages, as well as structure features, will become more apparent as the description of the invention proceeds.

The invention, therefore, comprises the combination of the conventional spring urged accelerator rod and a depressor bar combined through a pivotal connection and controlled by a spring and stop lug arrangement during ordinary operations of the depressor bar. In this arrangement the depressor bar, through the pivotal connection and spring and lug control, in effect, furnishes a continuation of the accelerator rod into a comfortable position immediately to the rear of the conventional brake pedal so that extraordinary motion of the depressor bar in a direction toward the brake pedal will release pressure upon the accelerator rod and form the beginning of pressure upon the brake pedal.

For a full and more complete understanding of my invention reference may be had to the following description and accompanying drawing in which

Figure 1 is a sectional view of a floorboard of a car with my invention arranged in place with respect to other associated parts.

Figure 2 is, in effect, an end view taken from a position looking forwardly from the driver's seat.

Referring now to the drawing, the ordinary floorboard of a car comprises a pair of angularly disposed plates 5 and 6 or a single plate formed with a pair of such parts in angular relation to each other. The conventional brake operating shaft 7 is carried in appropriate bearings beneath the floorboard and a brake lever 8 is keyed thereto so that downward motion of the lever 8, through application of pressure upon a pedal pad 9, will cause a rocking motion of the brake shaft. A conventional accelerator rod 10 is mounted beneath and through various connections including a spring return is effective to cause opening and closing of the carburetor valve. Up to this point all parts are customary and found in one form or another in the usual modern day automobile.

Ordinarily, an opening is provided in the floorboard to the right of the brake pedal pad 9 and through this opening a rod protrudes so that downward pressure thereon will depress the accelerator rod and cause an opening of the carburetor valve. In my present invention I contemplate the formation of such an opening, as indicated at 11, immediately to the rear of the brake pedal pad 9. In view of this location of

the opening 11 the upper end of accelerator rod 10 is then formed or arranged to end at a point in registry with the opening 11 and, preferably, a screw thread 12 is formed on the upper end of the accelerator rod to receive a block 13 which is provided with a pair of spaced ears 14 in which are formed a pair of transversely aligned pivot openings. A depressor bar 15 carries a channel construction at its lower end which provides a pair of spaced pivot ears 16 in which a pair of transversely aligned openings is provided. A stop lug 17 is carried at the lower end of the depressor bar 15 and a foot rest pad 18 is arranged at the upper end of the depressor bar.

Within the channel provided by ears 16 is arranged one tongue of a spring 19 and an intermediate loop of the spring 19 is arranged around a pivot pin 20 with the other free end of spring 19 resting upon pivot block 13. The loop of the spring, thus, is housed between the ears 16 and the ears 14 and due to the tension of the spring the depressor bar 15 and accelerator rod 10 are kept in substantially straight alignment although the lug 17 prevents a complete alignment so that there is always a slight angle to permit the inauguration of a pivoting action upon the pin 20 as later to be described.

A leaf spring 21 having a downwardly depending tongue is secured to the back of the brake pedal pad by appropriate screws and is thus in proper position to contact pad 18 when the depressor bar 15 is swung forwardly on pivot 20 to the position shown in dotted lines.

The operation of my invention may be understood from the foregoing but a brief description will be given. The driver feeds gasoline to the car by pressing his foot downwardly upon pad 18 in a direction indicated by the arrow immediately above and to the rear of pad 18. Due to the fact that depressor bar 15 and accelerator rod 10 are in substantial alignment the force exerted will cause a downward travel of the accelerator rod and a consequent opening of the carburetor valve. It is understood that the spring 19 and stop lug 17 aid in maintaining this alignment during the desired acceleration of the car. If the need for a quick stop arises and the driver involuntarily pushes his foot in a forward direction the resistance to pivoting action offered by spring 19 is overcome and the depressor bar 15 swings around pivot 20 toward the brake pedal 9. When this motion is complete the pad 18 comes in contact with spring 21 and the driver's foot is already causing a depression of the brake pedal to bring the car to a halt. It can be seen that the brake pedal pad 9 and the accelerator pad 18 will both be pushed forwardly during the brake application and, of course, the spring control of accelerator rod 10 will cause its upper end to return to idling position. When the driver removes his foot from the brake pedal pad 9 the spring return control thereof will return the pedal to the position indicated in Figure 1 and the spring 21 will tend to flip the depressor bar 15 into the position shown in Figure 1 also, even though the major portion of this return operation is accomplished by the tension of spring 19. The brake return springs, thus, aid in "resetting" the depressor bar 15 for further gas feeding operations.

From the operations above described it can be seen readily that the driver may use his right foot or left foot for gas feeding or brake applying operations with great safety. In some modern cars there are no clutch pedals but the

tendency of most drivers is to shove both feet forwardly at the time of an emergency. Thus, on long trips a driver might wish to feed gas with his left foot so as to afford a rest for his right foot. In this case the ordinarily automatic motion of his left foot to engage the clutch pedal would stop the gas feeding operation and apply the brake in a short period of time.

Various modifications of the various parts and arrangements may be made without departing from the spirit of my invention and I do not wish to be limited to the exact arrangement and construction shown but wish to avail myself of all variations coming properly within the scope of the appended claims.

I claim:

1. Apparatus of the character described comprising in combination a floorboard having brake lever opening therein with an accelerator opening to the rear thereof, a brake pedal for reciprocating motion in said first mentioned opening with a pedal and arranged above said floorboard, an accelerator control apparatus mounted beneath said floorboard and having an end in registry with said second mentioned opening, a depressor bar pivotally mounted on said accelerator rod end, means for yieldably maintaining said accelerator rod and depressor bar substantially in alignment for transfer of motion during downward thrust of said depressor bar, and means associated with said brake lever for aiding in restoring said substantial alignment after pivotal motion of said depressor bar with respect to said accelerator rod.
2. Apparatus of the character described comprising in combination a floorboard having brake lever opening therein with an accelerator opening to the rear thereof, a brake pedal for reciprocating motion in said first mentioned opening with a pedal and arranged above said floorboard, an accelerator control apparatus mounted beneath said floorboard and having an end in registry with said second mentioned opening, a depressor bar pivotally mounted on said accelerator rod end, means for yieldably maintaining said accelerator rod and depressor bar substantially in alignment for transfer of motion during downward thrust of said depressor bar, and means for aiding in restoring substantial alignment after pivotal motion of said depressor bar with respect to said accelerator rod.
3. Apparatus of the character described comprising a reciprocating accelerator rod and control apparatus, a depressor bar pivotally mounted on said accelerator rod, and means for yieldably maintaining substantial alignment between said depressor bar and accelerator rod during downward motion of said depressor bar.

4. Apparatus of the character described comprising a reciprocating accelerator rod and control apparatus, a depressor bar pivotally mounted on said accelerator rod, and means for yieldably maintaining substantial alignment between said depressor bar and accelerator rod during downward motion of said depressor bar, and means for aiding in restoring said substantial alignment after pivotal motion of said depressor bar with respect to said accelerator rod.

5. In a vehicle having accelerator control apparatus and a brake lever operable from the interior of said vehicle the improvement which comprises a reciprocating accelerator rod in operable juxtaposition to said brake lever, a de-

pressor bar pivotally mounted on said accelerator rod in the general plane of movement of said brake lever, means for yieldably maintaining substantial alignment between said depressor bar and accelerator rod to transmit a longitudinal motion of said depressor bar, and means for aiding in restoring said substantial alignment

5 after pivotal motion of said depressor bar with respect to said accelerator rod has carried said depressor bar toward said brake lever, said last mentioned means including a leaf spring carried by said brake lever.

AUGUST D. KUMPF.
